(57) **CLAIM**

The ornamental design for a condiment dispenser nozzle, as shown and described.

DESCRIPTION

FIG. 1 is a perspective view of a condiment dispenser nozzle constructed in accordance with one preferred embodiment of the invention.

FIG. 2 is an elevational view of the front of the condiment dispenser nozzle shown in FIG. 1;

FIG. 3 is an elevational view of the rear of the condiment dispenser nozzle shown in FIGS. 1 and 2; and,

FIG. 4 is an elevational view of a side of the condiment dispenser nozzle shown in FIGS. 1, 2 and 3, the opposite side of the condiment dispenser nozzle being a mirror image of the side shown in FIG. 4.

The broken lines are for illustrative purposes only and form no part of the claimed design.
